UNITED STATES PATENT OFFICE.

JOHN ABEL, OF JERSEY CITY, NEW JERSEY, ASSIGNOR TO MERSEREAU METAL BED COMPANY, A CORPORATION OF NEW JERSEY.

DESIGN FOR A CAP OR VASE FOR METAL BED-FRAMES.

48,577.

Specification for Design.

Patented Feb. 22, 1916.

Application filed September 1, 1915. Serial No. 48,555. Term of patent 7 years.

To all whom it may concern:

Be it known that I, JOHN ABEL, a citizen of the United States, residing at Jersey City, in the county of Hudson and State of New Jersey, have invented a new, original, and ornamental Design for a Cap or Vase for Metal Bed-Frames, of which the following is a specification, reference being had to the accompanying drawing, forming part thereof.

The figure is an elevation of a cap or vase for metal bed frames.

I claim:

The ornamental design for a cap or vase for metal bed frames, as shown.

JOHN ABEL.
